UNITED STATES PATENT OFFICE.

ALVAH W. FOWLER, OF THRIFTY, TEXAS.

HAME-FASTENER.

1,102,032.

Specification of Letters Patent. Patented June 30, 1914.

Application filed January 31, 1914. Serial No. 815,722.

To all whom it may concern:

Be it known that I, ALVAH W. FOWLER, a citizen of the United States, residing at Thrifty, in the county of Brown and State 5 of Texas, have invented certain new and useful Improvements in Hame-Fasteners, of which the following is a specification.

The present invention relates to improvements in hame fasteners, with the primary 10 object in view of providing a simple locking device, capable of being cheaply manufactured, for quickly and adjustably connecting together collar hames.

In carrying out the invention I have provided a pair of telescoping members, one 15 of which carries a spring actuated locking member adapted to engage the other of said telescoping members to hold them in adjusted position, with an operating member 20 constituting a lever connected to the locking member and coöperating with the second mentioned telescoping member whereby to disengage the former to permit separation or disconnection of the telescoping 25 members aforesaid.

Another object lies in the provision of a spring for the locking member normally holding the same in its locking position and which spring also performs a dual function 30 in that it acts as a retainer for the hame member engaged with its coöperating telescoping member.

With the above and other objects in view, this invention consists in the construction, 35 combination, and arrangement of parts all as hereinafter more fully described, claimed and illustrated in the accompanying drawings, wherein;

Figure 1 is a view in elevation of the device 40 constructed in accordance with my invention; Fig. 2 is a longitudinal sectional view therethrough; Fig. 3 is a bottom plan of the invention; and Fig. 4 is a vertical sectional view on the line 4—4 of Fig. 1.

Throughout the following detail description, and on the several figures of the drawings, similar parts are referred to by like reference characters.

As illustrative of the invention, referring 50 to the drawings, the numerals 1 and 2 represent a pair of coöperating hame engaging members, the former consisting of a slightly curved bar having formed on its under surface spaced teeth 3, and the latter comprising 55 a shell to receive the first mentioned member. Each of the hame engaging mem-

bers is bent to form the hame engaging hooks 4, 5, adapted to receive the lower extremities of the conventional collar hame, the position of which around the collar may 60 be adjusted to the proper size by my invention, and the terminals of these members extend a suitable distance downwardly to provide manipulating members or handles 4', 5'. The member 2 is stamped or 65 formed from a flat piece or sheet of metal, the longitudinal edges of the body portion of which are bent at angles so as to constitute spaced flanges 6, 7, whereby to provide a shell into which the toothed hame engaging member 1 is introduced in adjusting the 70 hames together.

Between the flanges 6, 7, and adjacent to the end portion of the same, is pivotally mounted a locking member or dog 8, carried by the pivot 9 and this member is engageable with the teeth 3 of the hame engaging member 1 when the latter is inserted into the shell aforesaid, being held normally in such interlocking engagement by the leaf 80 spring 10 connected at one end to the dog by any desired means, such as the rivet 11. As will be noted particularly by reference to Figs. 2 and 3, the spring 10 extends longitudinally of the shell between the flanges 85 6 and 7, substantially closing the opening therebetween, and across the hame hook 5 for which it acts as a closure member, passing beneath the retaining ring 12 formed by bending the metal adjacent to the ends of 90 the shell together.

To disengage the dog 8 from the teeth 3, I provide a loop or ring 13 which passes into the free end of the dog, said ring constituting an operating lever to perform this function. It is especially designed that the ring 95 13 shall conform in width to the width of the shell, the flanges 6 and 7 of which are notched at 14 so that in the action of disengaging the dog by movement of the ring 100 laterally into the dotted line position shown in Fig. 1, said ring rides on or presses against the edges of the notches, withdrawing the dog from locking position. Not only does this ring act as an operating member 105 for the dog as just described, but such movement laterally of the member as hereinbefore described also is capable of moving the spring 10 longitudinally so as to withdraw the extremity of the same from across 110 the hook 5 whereby to permit the insertion of the hame member into said hook. The

other hook 4 is also provided with a closure member in the form of a short spring 15 secured by the fastening member 16 to the shank of the member 1 and this spring ex- 5 tends through the retaining ring 17 similar in function and formation to the ring 12.

In the actual use of my device, as hereinbefore described, each of the hame engag- 10 ing members 1 and 2 is connected with the respective hame members, and the telescoping of said members 1 and 2, by the inser- 15 tion of the former into the shell portion of the latter, is a matter of merely sliding the toothed portions over the dog 8, the teeth 3 being formed or inclined so as to enable this to be done without operating the dog. The peculiar coöperation of the springs 10 and 15, with the respective members to which they are connected, is advantageous in that 20 the telescoping members are effectively prevented from rattling and the construction of the device is simple, enabling it to be cheaply manufactured for use with harness hames.

25 Having thus described my invention, what I claim is:—

1. In a hame fastener, the combination with a pair of coöperating hame engaging members, of a locking member for adjust- 30 ably holding said members in adjusted position, means normally holding said locking member in locking engagement, and means operable on one of the hame engaging members to disengage the locking member.

35 2. In a hame fastener, the combination with a pair of coöperating hame engaging members, of a locking member for adjust- 40 ably holding said members in adjusted position, and an operating lever connected to the locking member and movable into contact with one of the hame engaging members whereby upon pressure thereagainst to disengage the locking member aforesaid.

45 3. A hame fastener including hame en- gaging members, one of which is provided with teeth, a locking pawl connected to the other of said hame engaging members, spring means coöperating with the pawl and one of the hame engaging members

to hold the same in locking engagement 50 with the teeth aforesaid, and an operating member constituting a lever connected with the pawl and movable to disengage the pawl from the teeth, said spring means coacting with the hame engaging member to form 55 retaining means for a hame connected to the latter.

4. A hame fastener including a hame en- gaging member provided with teeth, a co- 60 operating hame engaging member adapted to receive the first mentioned member, a locking pawl pivoted to the second hame en- 65 gaging member, and a spring connected to the pawl to place the same under tension whereby to hold said pawl in engagement 70 with the teeth when said hame engaging members are connected together, each of said hame engaging members having a hame hook for attachment to a hame and said spring co-acting with the hook of its co- 75 operating hame engaging member to form retaining means for the hame inserted therein.

5. A hame fastener including telescoping hame engaging members, each having a hame 75 engaging hook for attachment to a hame, means for adjustably connecting said hame engaging members together, and independent retaining members coöperating with the hook aforesaid for locking the hames there- 80 in one of said retaining members comprising a spring connected to the connecting means aforesaid for normally holding said means in locking position.

6. A hame fastener comprising a toothed 85 bar, a shell, each having a hame engaging hook, springs closing said hooks, flanges on the shell for retaining the springs in position on said members, and a locking pawl, one of the springs being connected to the 90 pawl to place the same under tension.

In testimony whereof I affix my signature in presence of two witnesses.

ALVAH W. FOWLER.
